UNITED STATES PATENT OFFICE.

EMIL KAROW, OF SARLES, NORTH DAKOTA, ASSIGNOR OF ONE-HALF TO ED GARWICK,
OF SARLES, NORTH DAKOTA.

AUTOMOBILE LIFTING DEVICE.

Application filed June 7, 1926. Serial No. 114,305.

The object of this invention is to provide a device for automatically lifting a motor car when the latter is driven on to the apparatus, the latter including a longitudinally 5 inovable element and means cooperating therewith for engagement by a car axle, said element acting to rock a plurality of horizontal shafts carrying cams which engage pivotally mounted levers extending beneath the axles of the car and adapted to 10 lift the latter.

A further object is to provide controlling means of the type hereinafter disclosed.

A further object is to provide wheel engaging means automatically thrown to operative position when the car is elevated, said means being released by the operation of a hand lever.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a top plan view of the construction.

Figure 2 is a bottom plan view.

Figure 3 is a view in side elevation.

Figure 4 is also in side elevation, the elements below the car wheels having moved to lower position.

Figure 5 is a view in longitudinal section.

Figure 6 is also in longitudinal section, the car lifting element having been raised.

Figure 7 is a transverse section on line 7-7 of Figure 5.

Figure 8 is a detail view of certain rack and rack engaging means described below.

Figure 9 is a detail view in plan showing features of the construction described below.

Figure 10 is a detail view of an axle engaging device.

Figure 11 is a verticle sectional view through the yoke 43.

The stationary portion of the structure includes a platform 10, vertically extending longitudinal bars or rails 11 and 12, and runways 13 and 14. The platform 10 is mounted on transversely extending supports or timbers 15 and 16, and extending from the ends of the runways 13 and 14 are

pivottally mounted elements, such as 17, the 55 pivotal connection being effected by means of pins 18 passing thru ears 19. These elements 17 provide inclined planes, permitting of the easy approach of the car and permitting the latter to leave the apparatus 60 without perceptible jarring movement.

Carried by the runways 13 and 14 are wheel engaging devices each comprising a plurality of hingedly connected sections 20 and 21, the hinge or pivotal connection being designated 22, and one of these elements having its outer end portion hinged at 23 to the runway, while the other element or section 20 is movable longitudinally of the runway to a limited extent in view of a pin 70 and slot connection, the pin being designated 24 and the slot extending thru the runway being shown at 25.

Pins 24 may each constitute an eye bolt or the like, the eye portion 26 having connection with a cord such as 27 passing over a winding device or sleeve, also constituting a winding drum and designated 28. Another cord or chain 30 passes around this winding device 28 in the opposite direction, and passes around a pulley or roller 31 mounted in a bracket or the like 32, the flexible element 30 having connection with an eye bolt 33 passing thru a slot 34 in the runway 14. This bolt or pin 33 is connected with segment 20' of a wheel engaging device, such as that previously described, and including besides element 20' a hingedly connected element 21', this device last named having the same function as element 21 at 90 the opposite end of the apparatus.

A similar construction is provided for runway 13, and it will be observed that upon winding drum 28, the elements 20, 21 and elements 20' and 21' will be elevated to the 95 position of Figure 3, a winding drum 28' on the side of the apparatus opposite element 28, serving the same purpose and having connection with a flexible device 30', as in the case of the assembly on the side of 100 the machine in which the operative elements have been described in full.

Figure 7 shows the drums 28' and 28, and these elements each carry rigidly therewith clutch elements 36 cooperating with clutch 105 elements 37 rigid on horizontal shaft 38, the latter extending transversely of the mounting element or timber 15. Element

38 constitutes a rock shaft, and the sleeves 28 and 28' are normally in operative relation with shaft 38, so that when the latter is rocked sleeves or drums 28 and 28' will be rotated, for throwing upwardly the wheel engaging devices comprising elements 20 and 21, and the other pairs of elements of similar character. The clutches are held in engagement by springs 39 and 39'.
 10 The end portions of the drums 28 and 28' are notched and constitute wheels 40 and 40' for engagement by pawls 41 and 41' pivoted to the edge portions of the runways. The sleeves or drums 28 and 28' are further provided with annular grooves such as 42 for engagement by yokes 43 and 43'. One of these yokes is connected with a rod 44 slidably mounted in transverse element 15 of the stationary structure, and the yoke 43' is connected with rod 44' slidably thru element 15 of the stationary structure and having pivotal connection with the lower slotted end of hand lever 45. This lever is fulcrumed at 46, and on the side of the pivotal point of this lever opposite to that where connection is effected with rod 44', a pin and slot connection 47 is provided with rod 44. In view of the connections with lever 45 on opposite sides of the pivotal point or fulcrum, the yokes 43 and 43' and therefore the drums 28 and 28' will be moved simultaneously in the direction required for releasing the clutches at 36 and 37, by slidable movement of the drums outwardly on each side of the main structure.
 15 Shaft 38 is rocked automatically when the car is driven onto the apparatus, and when engagement is effected with means for throwing to elevating position a plurality of axle-lifting levers designated 50 and each pivotally mounted near one end in a stationary portion of the structure, in the manner indicated at 51. The position of elements 20 and 21 and corresponding elements 20' and 21' of each pair is shown in Figure 3, the axle-lifting lever 50 having been raised. In Figure 4 the wheel engaging devices 20 and 21 and 20' and 21' on that side of the machine nearest the observer have dropped to horizontal position, preparatory to releasing the car, because the clutches associated with the winding drums 28 and 28' have been thrown out by hand lever 45, and the elements on the opposite side of the apparatus, which engaged the wheels on that side, as in the case of devices 20 and 21, have also dropped to horizontal position, because of the simultaneous release of the clutch controlled drums, thru rods 44 and 44' connected with lever 45.
 20 Axle engaging levers 50 are lifted by cams 55 rigidly mounted on rock shafts 56 and 57, and guiding plates, such as 58, carried by the cam elements retain the free ends 50' of the levers in the required position.
 25

tion, so that they are guided in their vertical movement. Shafts 56 and 57 each carry a plate element 59 or 59' as the case may be, these devices constituting crank members having pivotal connection with longitudinally movable bars 61 and 62. These bars are each provided with teeth as indicated at 63, and a device constituting a dog or pawl of unusual form is designated 64, being pivotally mounted at 65 in a bracket 66, and extending entirely across longitudinally movable elements 61 and 62, spaced as shown, so that upon the operation of dog 64 the bars 61 and 62 are engaged or released simultaneously.
 30

Connected with longitudinally movable bars 61 and 62, or with one of the bars are means for rocking shaft 38 mounting the drums 28 and 28'. In Figure 7 this operation or connection for effecting the rocking of shaft 38 is by means of crank 68, and when the axle-lifting levers 50 are raised, shaft 38 is rocked for the purpose of lifting wheel engaging devices 20 and 21 as before indicated, and as shown in Figure 3.
 35

A forked arm 70 is engaged by axle 71 of the car, when the latter is driven on to the apparatus. Lever or arm 70 is pivoted at 72, and apertures or recesses 73 in the side of element 70 are engaged by a spring-held pin 74, acting as a holding device for the element 70.
 40

A slide 75 is movable longitudinally in channelled element 76 and is pivotally connected by means of link or the like 77 and a short link or hinge connection at 78, with plate member 59' which constitutes a crank operating device for rocking shaft 57.
 45

Slide 75 also mounts a resilient member 80, having an upper flat surface, and having an angular or bent-over portion 81 for engagement by the lower end of arm 70. This resilient element further includes a horizontally extending portion 82 extending under transverse pin or bar 83, the ends of which project thru slots 84 in the sides of the channel element 76.
 50

The resilient element including portion 80 is connected with the slide 75 by means of pin 85, and this connection being somewhat loose, the operation of the resilient device is controlled in part by spring 86 surrounding pin 87, the spring bearing on the upper surface of element 80. The lower portion of pivoted arm 70 includes a curved or cam surface 70' adapted to engage the angular portion 80' of the resilient device, permitting one of these elements to pass the other in a manner well understood, but when the pivoted element 70 and resilient arm 80 and its angular portion 80' are in the position of Figure 5 there is engagement of a positive character, and assuming that the car is moving towards the left, the axle 71

engaging the forked portion of arm 70, the slide 75 will be thrown toward the right, and will throw crank 59' and therefore rock shaft 57 moving the cams 58 carried thereby to upper position for raising axle-lifting levers 50. The same operation results at the opposite end of the apparatus, because of the rocking of shaft 56 and the raising of the cams carried thereby.

10 The dog 64 is controlled by crank arm 64' carried by rock shaft 64''. An arm 65' connected with shaft 64'' is controlled by hand lever 45', this lever extending alongside of lever 45 and within convenient reach of the operator, who need not leave the car in order to control or operate either hand lever.

15 Tripping arm or pivoted arm 70 is shown in Figure 5 in position for engagement by the car axle in moving onto the lifting device, and in Figure 6 the tripping arm having been thrown by the forward movement of the car, is in position for being thrown in the opposite direction when the car is backed off and the axle 71 engages the fork of the pivoted arm or tripping arm 70. The lower end of element 70 will pass the angle portion 80' of the resilient device 80, and the element 50 will be in position for a new 20 operation. In lowering the car the release of dog or holding element 64 permits longitudinal bars 61 and 62 to move to the left under the weight of the car on axle-lifting levers 50 which return to normal position 25 by gravity.

Having described the invention what is claimed is:—

1. In a device of the class described, a plurality of pivotally mounted axle-lifting levers, cams engaging the levers, rock shafts mounting and operating the cams, a longitudinally movable device operatively connected with the rock shafts, and wheel engaging devices operatively connected with the longitudinally movable device and automatically thrown to operative position upon the elevation of the levers by the cams.

2. In a device of the class described, a plurality of pivotally mounted axle-lifting levers, cams engaging the levers, rock shafts mounting and operating the cams, a longitudinally movable device operatively connected with the rock shafts, a tripping arm for engagement by an axle for shifting the longitudinally movable device, and wheel engaging devices operatively connected with the longitudinally movable device and automatically thrown to operative position upon the elevation of the levers by the cams.

3. In a device of the class described, a plurality of pivotally mounted axle-lifting levers, cams engaging the levers, rock shafts mounting and operating the cams, a longitudinally movable device operatively connected with the rock shafts, a tripping arm

for engagement by an axle, a resilient element carried by the longitudinally movable device for positive engagement by the tripping arm upon movement of the latter in one direction, and wheel engaging devices 70 operatively connected with the longitudinally movable device and automatically thrown to operative position upon the elevation of the levers by the cams.

4. In a device of the class described, a plurality of pivotally mounted axle-lifting levers, cams engaging the levers, rock shafts mounting and operating the cams, a longitudinally movable device operatively connected with the rock shafts, and wheel engaging devices operatively connected with the longitudinally movable device and automatically thrown to operative position upon the elevation of the levers by the cams, and means including cable winding and unwinding mechanism for releasing the wheel engaging devices.

5. In a device of the class described, a plurality of pivotally mounted axle-lifting levers, cams engaging the levers, rock shafts mounting and operating the cams, a longitudinally movable device operatively connected with the rock shafts, and wheel engaging devices each comprising a plurality of pivotally connected sections simultaneously operated, and operatively connected with the longitudinally movable device for automatic operation with said levers.

6. In a device of the class described, a plurality of pivotally mounted axle-lifting levers, cams engaging the levers, rock shafts mounting and operating the cams, a longitudinally movable device operatively connected with the rock shafts, and wheel engaging devices operatively connected with the longitudinally movable device and automatically thrown to operative position upon the elevation of the levers by the cams, a pivotally mounted axle operated element, and means for operating the longitudinally movable element by the axle operated element.

7. In a device of the class described, a plurality of pivotally mounted axle-lifting levers, cams engaging the levers, rock shafts mounting and operating the cams, a longitudinally movable device operatively connected with the rock shafts, and wheel engaging devices operatively connected with the longitudinally movable device and automatically thrown to operative position upon the elevation of the levers by the cams, a pivotally mounted forked arm positioned for engagement and operation by a car axle, and an angular resilient member on the longitudinally movable device and engaged by the forked arm.

8. In a device of the class described, a supporting structure including runways, a plurality of pairs of elements mounted on

the runways, each pair comprising pivotally connected sections, one of the sections of each pair having slidable connection with the runway on which it is carried, a shaft 5 and means for rocking the shaft upon movement of a car onto the structure, flexible members and winding devices therefor, said

flexible members having connection with the pivoted and slid able elements mounted on the runways and clutch mechanism between 10 the shaft and each winding device.

In testimony whereof I affix my signature.

EMIL KAROW.
